A. G. LIEBMAN.

RAIL CHAIR.

APPLICATION FILED JAN. 23, 1915, RENEWED DEC. 21, 1917.

1,279,723.

Patented Sept. 24, 1918.

UNITED STATES PATENT OFFICE.

AUGUST G. LIEBMAN, OF CHICAGO, ILLINOIS.

RAIL-CHAIR.

1,279,723.

Specification of Letters Patent. Patented Sept. 24, 1918.

Application filed January 23, 1915, Serial No. 4,024. Renewed December 21, 1917. Serial No. 208,335.

To all whom it may concern:

Be it known that I, AUGUST G. LIEBMAN, a citizen of the United States, residing at Chicago, in the county of Cook and State of Illinois, have invented certain new and useful Improvements in Rail-Chairs, of which the following is a specification.

This invention relates to railway track appliances and more particularly to a rail chair of that general type shown and described in U. S. Letters Patent No. 1,126,534, issued to me on the 26th day of January, 1915.

The object of the invention is generally to improve and simplify the construction of the chair and fastening device, whereby to reduce the cost of manufacture and render the chair more efficient in operation.

A further object of the invention is to construct the chair as to resist the action of the wheels of derailed cars and to house and protect the screw spikes or primary fastening devices.

A further object of the invention is positively to prevent displacement of the rail engaging members, after they have been adjusted for gage.

A further object of the invention is to provide the bed plate of the chair with abutments of equal height to facilitate side shimming and also to permit the bed plate and rail engaging members to be rolled to greater advantage.

A still further object of the invention is to provide a rail chair capable of being used either on old or new ties and which will effectually eliminate mechanical wear to the ties, and consequently prolong the life of treated or untreated ties by providing for lateral and vertical adjustment of the rail without the necessity of disturbing the primary fastening devices or respiking or shifting the bed of the chair on the tie to effect such adjustments.

Further objects and advantages will appear in the following description, it being understood that various changes in form, proportions and minor details of construction may be resorted to within the scope of the appended claims.

In the accompanying drawings:

Figure 1 is a perspective view of a rail chair embodying the present invention;

Fig. 2 is an end elevation, partly in section, showing the base and side shims in position and the rail adjusted for surface;

Fig. 3 is a top plan view of Fig. 1;

Fig. 4 is a detail perspective view of one of the rail engaging members detached.

Corresponding and like parts are referred to in the following description and indicated in all the views of the drawings by the same reference characters.

Referring to the drawings, A represents a rail having a standard cross section, and B a tie supporting the rail.

Disposed upon the tie, is a bed plate 5, preferably a rolled shape and substantially rhomboidal in form, said plate preferably extending the entire width of the tie so as to form an extended plate support and thus prevent cutting and crushing of inferior wood ties. The bed plate is provided with spaced pairs of upstanding flanges 6 and 7, of equal height, the outer flanges 6 being disposed at an angle to the short axis of the bed plate and the inner flanges 7 being disposed parallel with the outer flanges and constituting abutments.

The bed plate 5 is permanently attached to the cross tie by means of screw spikes 8 which pass through suitable openings 9 formed in the bed plate between the flanges 6 and 7, each screw spike being formed intermediate its ends with an annular shoulder 85 10 adapted to bear against the bed plate around the adjacent opening 9.

The rail A is held in place between the inner abutments 7 for lateral and vertical adjustment by means of rail engaging members 11. Each rail engaging member is provided with a tapered wedge-shaped portion 12 adapted to bear against the inner face of the adjacent abutment 7 and an inwardly extending clamping lip 13 which bears against the upper surface of the base flange of the rail and the web thereof, as best shown in Fig. 2 of the drawings. Each rail engaging member is also provided with a laterally extending web 14, the lower face 15 of which is smooth and unobstructed for engagement with the upper faces of the adjacent flanges 6 and 7 or for contact with suitable side shims 16 when the rail is adjusted vertically with respect to the chair for surface. The overhanging web 14 of each

rail engaging member is provided with a slot 17, the side walls of which are notched at 18 to receive the threaded extension 19 of a screw cap or secondary fastening device, indicated at 20. The cylindrical extension 19 of each screw cap is internally threaded for engagement with the upper threaded end of the adjacent spike, while the head of the screw cap is provided with 10 a laterally extending flange 21, there being a spring washer 22 interposed between the flange 21 and the upper face of the rail engaging member, as shown.

It will here be noted that the rail engaging members extend over the abutments and resist the action of the wheels of derailed cars, while the screw caps not only form a secondary fastening device for the chair, but also effectually house and protect the primary fastening devices. Again, it will be noted that the cylindrical extensions 19 of the screw caps, by engagement with the notches 18 in the rail engaging members, serve to positively prevent displacement of 25 said rail engaging members, after the latter have been adjusted to shift the rail for gage. It will now be obvious that by shifting one of the rail engaging members in one direction and the other in the opposite direction, 30 the rail may be adjusted laterally with respect to the bed plate for gage and the rail engaging members may be clamped securely in wedging engagement with the rail and with the abutments 7 by tightening the 35 screw caps. Inasmuch as the space between the abutments 7 is relatively wide, a maximum of lateral adjustment of the rail to gage may be effected.

The rail A may be vertically adjusted for 40 surface by loosening the screw caps and inserting a base shim 23 beneath the rail and side shims 16 between the lower faces of the rail engaging members and the upper faces of the abutments 6 and 7, the screw caps 45 being subsequently turned home so as to clamp the parts in adjusted position, as best shown in Fig. 2 of the drawings.

It will here be noted that by making the flanges 6 and 7 of equal height, side shimming is materially facilitated, while such construction of the flanges also permits the rail engaging members to be rolled to greater advantage than if the rail engaging members were to engage abutments of unequal height.

The flanges 21 of the screw caps compensate for recoil of the rail under stress and thus prevent fracture to the base flange of the rail.

It will thus be seen that the present chair provides for gage variations on curves and tangents and rail surface variations and shimming without respikeying and without the necessity of disturbing the primary fastening devices.

Having thus described the invention, what is claimed as new is:

1. A rail chair including a bed plate having spaced pairs of upstanding flanges of equal height, the inner flange of each pair constituting an abutment, rail engaging members adapted to bear against the upper faces of the flanges or against side shims, a fastening device disposed between the flanges of each pair and terminating short of the upper surfaces of the rail engaging members, and secondary fastening devices coacting with the rail engaging members and primary fastening devices and forming a protection for the said primary fastening devices.

2. A rail chair including a bed plate having spaced pairs of upstanding flanges, the inner flange of each pair constituting an abutment, rail engaging members adapted to bear against the upper faces of the flanges or against side shims and provided with slots, primary fastening devices disposed between the pairs of flanges, and secondary fastening devices extending through the slots and engaging the primary fastening devices for coaction with the rail engaging members.

3. A rail chair including a bed plate having spaced pairs of upstanding flanges, a primary fastening device disposed between the flanges of each pair for permanently securing the bed plate to a cross tie, rail engaging members adapted to bear against the upper faces of the flanges or against side shims, and screw caps engaging the primary fastening devices and bearing against the rail engaging members.

4. A rail chair including a bed plate having spaced pairs of upstanding flanges, rail engaging members having laterally extending webs bearing against the flanges and provided with slots, the walls of which are notched, a primary fastening device disposed between each pair of flanges and permanently securing the bed plate to a cross tie, and secondary fastening devices seated in the notches in the rail engaging members and engaging the primary fastening devices.

5. A rail chair including a bed plate having spaced pairs of upstanding flanges, a primary fastening device disposed between the flanges of each pair for permanently securing the bed plate to a cross tie, rail engaging members overhanging the flanges and adapted to bear against the upper faces of said flanges or against side shims, screw caps engaging the primary fastening devices and provided with circumferential flanges, and washers interposed between the flanges of the screw caps and the adjacent rail engaging members.

6. A rail chair including a bed plate having spaced pairs of upstanding flanges of

equal height, a screw spike disposed between the flanges of each pair, rail engaging members having inwardly extending rail clamping lips and provided with tapered wedge-shaped portions for contact with the inner faces of the adjacent flanges, each rail engaging member being provided with an overhanging web adapted to bear against the upper faces of the flanges or against side shims, there being slots formed in the webs, the walls of which are notched, screw caps having interiorly threaded cylindrical portions engaging the adjacent screw spikes and provided with circumferential flanges, and washers interposed between the flanges of the screw caps and the adjacent rail engaging members.

7. A rail chair including a bed plate having spaced pairs of upstanding flanges, slotted rail engaging members adapted to bear against the upper faces of the flanges or against side shims for holding a rail in different positions of lateral and vertical adjustment with respect to the bed plate, primary fastening devices for securing the bed plate to a cross tie, and secondary fastening devices extending through the slots in the rail engaging members and engaging the primary fastening devices and said rail engaging members for positively preventing accidental displacement of the rail engaging members after the latter have been adjusted to shift the rail.

8. A rail chair including a bed plate having spaced pairs of upstanding abutments, rail engaging members adapted to bear against the upper faces of the abutments or against side shims for holding a rail in different positions of lateral and vertical adjustment, primary fastening devices for permanently securing the bed plate to a cross

tie, and secondary fastening devices forming a protection for the primary fastening devices and co-acting with said rail engaging members.

45

9. A rail chair including a bed plate having spaced pairs of upstanding flanges, the inner flange of each pair constituting an abutment, rail engaging members adapted to bear against the upper faces of the flanges or against side shims and provided with slots, primary fastening devices disposed between the pairs of flanges, and secondary fastening devices having depending portions extending through the slots in the rail engaging members and between the adjacent flanges for engagement with the primary fastening devices.

50

55

10. A rail chair including a bed plate having spaced pairs of upstanding flanges of equal height, the inner flange of each pair constituting an abutment, rail engaging members adapted to bear against the upper faces of the flanges or against side shims and provided with slots, primary fastening devices disposed between the pairs of flanges, secondary fastening devices extending through the slots in the rail engaging members and between adjacent flanges for engagement with the primary fastening devices, said secondary fastening devices being provided with angular heads and laterally extending flanges, and yieldable means interposed between the flanges of the secondary fastening devices and the adjacent rail engaging members.
